United States Patent Office

Des. 185,349
Patented June 2, 1959

185,349

BRACELET LINK OR SIMILAR ARTICLE

Murray Lawrence Cowan, Brookline, Mass., assignor to Speidel Corporation, Providence, R.I., a corporation of Rhode Island

Application June 11, 1958, Serial No. 51,296

Term of patent 14 years

(Cl. D45—4)

Fig. 1.

Fig. 2.

Figure 1 is an enlarged perspective view of a bracelet link or similar article showing my new design, with the conventional end attachment member thereof being shown in broken lines.

I claim:

The ornamental design for a bracelet link or similar article, substantially as shown and described.
